APPARATUS FOR GENERATING GEARS

Gale E. Millhuff, Chicago, Ill., assignor to Goodman Manufacturing Company, Chicago, Ill., a corporation of Illinois

Application October 18, 1949, Serial No. 122,045

10 Claims. (Cl. 90—7)

1

This invention relates to improvements in apparatus for generating gears, and relates particularly to improvements in machines for generating a gear having varying curvilinear pitch and varying pitch radius.

In Sloane application Serial No. 702,724, filed October 11, 1946, now Patent No. 2,585,971, issued February 19, 1952, for Improvements in Gearing, there is disclosed a novel form of varying speed gearing in which the speed variations are attained by modifying the gear tooth so that the matching pinion will contact the gear teeth at varying points with respect to the tips and roots of the gear and pinion. In this form of varying speed gearing, varying speed sets of gears may be produced with round gear and pinion blanks and a concentric pinion shaped cutter having a standard tooth form. Such varying speed gearing may also be achieved with a standard pinion mounted eccentrically and an irregularly shaped gear blank, as may be clearly understood with reference to the aforementioned Sloane application.

Such varying speed gearing may be fabricated by a gear shaping machine as shown in Hlinsky application Serial No. 711,745, filed November 22, 1946, now Patent No. 2,602,374, issued July 8, 1952, Improvements in Apparatus for Producing Varying Speed Gearing. The apparatus according to said Hlinsky application is characterized by the use of gear sectors formed on a work support for the gear blank and by a meshing gear sector on a bell crank which is rocked by a cam to advance or retard the gear blank and work support in accordance with the varying speed at which the finished pinion and gear operate. In the aforesaid Hlinsky application a weight is employed to eliminate any backlash between the gear sector of the work support and the gear sector of the bell crank, and to urge the follower of the bell crank into contact with the cam at all times.

With the foregoing considerations in mind it is a principal object of this invention to obviate the use of such gear sectors for advancing and retarding the work support with respect to the work spindle, and to employ a pair of fixed cams for such advancing or retarding of the work support.

A further object is to afford a resilient linkage connecting the cam followers cooperating with the fixed cams, and to maintain through said resilient linkage a constant force on the cam follower employed for advancing or retarding the work support with respect to the work spindle.

2

Other objects and important features of the invention will be apparent from a study of the following specification taken together with the drawings, which illustrate an embodiment which the invention has assumed in practice. The invention is not intended to be limited in terms of the embodiment herein described, other embodiments being reserved, as may be defined by the scope of the claims subjoined.

10 In the drawings:

Figure 1 is a plan view of a portion of a gear shaping machine embodying the improvements according to the present invention;

15 Figure 2 is a front elevation view of a gear shaping fixture according to the present invention;

20 Figure 3 is a section taken along the line 3—3 of Figure 2 looking in the direction of the arrows, and showing details of the external cam for advancing or retarding the work support with respect to the work spindle, and an internal cam for applying a constant load to the cam follower cooperating with the external cam; and

25 Figure 4 is a section taken along the line 4—4 of Figure 3 looking in the direction of the arrows.

Referring now particularly to Figures 2 and 4, the fixture according to the present invention may be used in connection with the bed 10 of a gear shaping machine having a hollow work spindle 11 turning therein. The hollow work spindle 11 is provided with a cap 12 which is held in position by a plurality of socket head screws 13. The cap 12 supports a vertical spindle 14 having a hub 15 which is held to the cap 12 by bolts 16.

35 A cam follower support plate 17 is supported on the hub 15 and is fastened thereto by screws 18, and is provided with a pair of arms 19 and 21, see Figure 3, to provide a support for a cam follower arm 22 pivoted at 23 thereto, and to provide a support for a second cam follower arm 24 pivoted thereto as at 26. It will be apparent that the hollow spindle 11, the spindle and hub 14, 15, and the support plate 17, together with the cam follower arms 22 and 24, will rotate together as a unit.

40 Means are provided for support of a gear blank 27 adapted to rotate with respect to the work spindle 11, and additionally to be advanced or retarded in its movement with respect to the work spindle 11, in order to provide for a varying curvilinear pitch of the finished gear made from the blank 27, and to be acted upon by a pinion-shaped cutter 28 mounted on a reciprocating and rotating arbor 29 which is controlled 45 in its movement with respect to the spindle 11.

The details of the control of the movement of the pinion-shaped cutter 28 on the arbor 29 form no part of the present invention, and are well known in the art. As shown in Figure 2, the pinion-shaped cutter 28 may be located eccentrically of the arbor 29 in order to provide both varying pitch radius and varying curvilinear pitch of the gear made from the gear blank 27.

The gear blank 27 is adapted to be mounted on a work support 31 which includes a sleeve 32 surrounding the spindle 14. The sleeve 32 is secured to the work support 31 by means of screws 33. A sleeve 35 having a slight amount of external taper is fitted around the sleeve 32. The sleeve 35 has a flange 34 provided with a milled slot 36, see also Figure 3, which is engaged by a stop 37 fastened to the support by a bolt 38. The flange 34 and the work support 31 are bored respectively as at 39 and 41, at a plurality of circumferentially spaced points to receive a spring 42 which will permit a certain amount of resilient movement of the tapered sleeve 35 with respect to the sleeve 32. The sleeve 35 is provided with a key 43 held thereto by the screws shown, which is adapted to fit within a keyway of the gear blank 27. In practice, the gear blank 27 is formed with a tapered central opening and a keyway adapted to register with the key 43 so that the gear blank 27 may be held firmly on the tapered sleeve 35 without the possibility of rotation with respect thereto.

The work support 31 is provided with an annular ring 44 held thereto by socket head screws 46, to provide a rest for the gear blank 27 on the work support 31. It will be apparent that the springs 42 will enable the sleeve 35 to be moved down when engaging the tapered bore of the gear blank 27 until the gear blank 27 rests upon the annular support ring 44. The tapered sleeve 35 is prevented from being forced off the sleeve 32 by a spanner retaining nut 45 threaded to sleeve 32. The gear blank 27 is held in position on the tapered sleeve 35 by means of a spanner nut 46 and a washer 47 which are threaded to sleeve 32.

Means are provided for advancing and retarding the movement of the gear blank 27 with respect to the work spindle 11 in accordance with the change of curvilinear pitch of the finished gear. To this end a stationary cam 48 is provided, which rests upon a support plate 49, the cam being held to the support plate 49 and properly located by means of a dowel 51 and a plurality of socket head screws 52, see Fig. 4. The support plate 49, see also Figure 2, is secured to a bracket 53 which in turn is held to the table 10 by a bracket 54. The cam 48 and the support 49 are provided with a bushing 56 surrounding the hub 15 and having a flange 57 which rests upon the cap 12.

Since the cap 12 and the arm 17 rotate with the work spindle 11, and since the cam 48 and the support plate 49 are held in a stationary position, the support plate 49 has secured thereto an annular wear plate 58 which rests upon the cap 12. The cam 48 is also provided with a similar annular wear plate 59 which underlies the support arm 17. Likewise, since the work support 31 is adapted to rotate with respect to the arm 17, the work support 31 is similarly provided with annular wear plates 61.

The cam 48 cooperates with means for advancing or retarding the work support 31 with respect to the work spindle 11 and the arm 17, and to this end the external cam 48 is engaged by a cam roller 62 mounted at the end of the cam

5 follower arm 22. As shown also in Figure 3, the cam follower arm 22 is connected by a link or clevis 63 which is connected by a pin 64 to the cam follower arm 22 and by a pin 66 to an arm 67 extending from the work support 31, see also Figure 4. It will be seen that as long as the cam roller 62 is in engagement with the surface of the external cam 48, and the work spindle 11 is turning, that the gear blank 27 will be advanced or retarded in its rotating movement with respect to the work spindle 11 according to the contour of the cam 48 at any point therealong. As shown particularly with reference to Figure 3, the cam 48 is substantially kidney-shaped, and it will be apparent that the cam roller 62 in following the contour of the cam 48 will first advance the work support 31 with respect to the work spindle 11 and then retard the work support 31 with respect to the work spindle 11.

Means are provided for exerting a constant pressure by the cam roller 62 against the surface of the cam 48. As shown with particular reference to Figures 2 and 4, an internal cam 68 is supported in position by an upright member 70 welded to the bracket 53. The internal cam 68 is substantially oval in shape and cooperates with a cam roller 71 mounted at the end of the arm 24. The other end of the arm 24 is connected by a pin 72 to a clevis member 73 which provides a housing for a spring 74 supported on a guide rod 76 provided with a head 77 forming an abutment for one end of the spring 74. The guide rod 76 is threaded into a clevis member 78 which is connected by a pin 79 to the arm 67. A closure member 81 is held to the housing 73 by a plurality of screws, not shown, and provides an abutment for the other end of the spring 74. It will be apparent that the load in the spring 74 may be adjusted by threading the rod 76 into the clevis member 78.

It will be apparent from the foregoing description that the spring 74 in tending to elongate will exert a pull on the arm 67 and will thus, through the clevis 63, exert a pull on the cam follower arm 22 so that the cam roller 62 is constantly in contact with the surface of the external cam 48. The linkage including the cam follower arm 24 and the clevis 73 is such that the load in the spring 74 will be maintained at a substantially constant value to be insuring that the cam roller 62 will bear against the external cam with substantially uniform pressure.

The upright member 70 supports a trough 82 which also provides a protective shield for the cams 68 and 48. The trough 82 is continuous with a downspout 83 to provide for removal of cuttings and cutting oil occasioned by the shaping operation of the gear blank 27.

According to the present invention there has been provided a novel and useful fixture for adapting a gear shaping machine for cutting gears having varying curvilinear pitch and varying pitch radius. According to the contour of the cams employed, the fixture may also be adapted for cutting gears having varying curvilinear pitch and constant pitch radius according to whether a concentric pinion cutter is employed or whether an eccentric pinion cutter is employed.

While the invention has been described in terms of an embodiment which it has assumed in practice, it is not intended to be limited in terms of the embodiment shown nor otherwise than by the terms of the claims appended.

I claim as my invention:

1. In a machine for generating a varying speed gear, a reciprocating pinion-shaped cutter rotatably driven at constant speed during its reciprocating movement, a rotating work spindle, a support for a gear blank mounted to rotate relative to said work spindle, means for advancing or retarding the rate of feed movement of said gear blank with respect to said work spindle in accordance with the relative speed ratio at which the finished gear and its mating pinion will operate comprising a stationary cam, a cam follower cooperating therewith and connected to said gear blank support, and means for urging said cam follower against said cam at substantially uniform pressure for all positions of said work spindle and said gear blank support comprising a second stationary cam, a second cam follower cooperating therewith and connected to said gear blank support.

2. The invention as defined in claim 1 characterized by a resilient connection between said second cam follower and said gear blank support.

3. The invention as defined in claim 1 characterized by resilient means connecting one of said cam followers to said gear blank.

4. In a machine for generating a varying speed gear, a reciprocating pinion-shaped cutter rotatably driven at constant speed during its reciprocating movement, a rotating work spindle, a support for a gear blank mounted to rotate relative to said work spindle, means for advancing or retarding the rate of feed movement of said gear blank with respect to said work spindle in accordance with the relative speed ratio at which the finished gear and its mating pinion will operate comprising a stationary cam having an external cam surface, a cam follower cooperating therewith and connected to said gear blank support, a second stationary cam having an internal cam surface, a second cam follower cooperating with said internal cam surface and a resilient connection between one of said cam followers and said gear blank support for urging the first said cam follower against said external cam at substantially uniform pressure for all positions of said work spindle and said gear blank support.

5. In a gear shaper for generating a gear having a varying pitch radius and a varying curvilinear pitch, a reciprocating eccentrically mounted pinion-shaped cutter rotatably driven at constant speed during its reciprocating movement, a rotating work spindle, a support for a gear blank mounted to rotate relative to said work spindle, means for advancing or retarding the rate of feed movement of said gear blank with respect to said work spindle in accordance with the relative speed ratio at which the finished gear and its mating pinion will operate comprising a stationary cam, a cam follower cooperating therewith and connected to said gear blank support, and means for urging said cam follower against said cam at substantially uniform pressure for all positions of said work spindle and said gear blank support comprising a second stationary cam, a second cam follower cooperating therewith and connected to said gear blank support.

6. The invention as defined in claim 5 characterized by a resilient connection between said second cam follower and said gear blank support.

7. The invention as defined in claim 5 characterized by resilient means connecting one of said cam followers to said gear blank.

8. In a gear shaper for generating a gear having a varying pitch radius and a varying curvilinear pitch, a reciprocating eccentrically mounted pinion-shaped cutter rotatably driven at constant speed during its reciprocating movement, a rotating work spindle, a support for a gear blank mounted to rotate relative to said work spindle, means for advancing or retarding the rate of feed movement of said gear blank with respect to said work spindle in accordance with the relative speed ratio at which the finished gear and its mating pinion will operate comprising a stationary cam having an external cam surface, a cam follower cooperating therewith and connected to said gear blank support, a second stationary cam having an internal cam surface, a second cam follower cooperating with said internal cam surface and a resilient connection between one of said cam followers and said gear blank support for urging the first said cam follower against said external cam at substantially uniform pressure for all positions of said work spindle and said gear blank support.

9. In a machine for generating a varying speed gear, a reciprocating pinion-shaped cutter rotatably driven at a constant speed during its reciprocating movement, a rotating work spindle, a support for a gear blank mounted to rotate relative to said work spindle on an axis coincident with the axis of said work spindle, means for advancing or retarding the rate of feed movement of said gear blank with respect to said work spindle in accordance with the relative speed ratio at which the finished gear and its mating pinion will operate comprising a stationary cam, a cam follower cooperating therewith and connected to said gear blank support, and resilient means for urging said cam follower against said cam at substantially uniform pressure for all positions of said work spindle and said gear blank support.

10. In a gear shaper for generating a gear having a varying pitch radius and varying curvilinear pitch, a reciprocating eccentrically mounted pinion-shaped cutter rotatably driven at constant speed during its reciprocating movement, a rotating work spindle, a support for a gear blank mounted to rotate relative to said work spindle on an axis coincident with the axis of said work spindle, means for advancing or retarding the rate of feed movement of said gear blank with respect to said work spindle in accordance with the relative speed ratio at which the finished gear and its mating pinion will operate comprising a stationary cam, a cam follower cooperating therewith and connected to said gear blank support, and resilient means for urging said cam follower against said cam at substantially uniform pressure for all positions of said work spindle and said gear blank support.

GALE E. MILLHUFF.
